ERNEST STROM AND REX L. ROCKWELL, OF ST. PAUL, MINNESOTA

FOLDING RACK AND TABLE FOR AUTOMOBILES

Application filed October 10, 1928. Serial No. 311,599.

Our invention relates to a folding rack and table of a type particularly adaptable for use on the running board of motor vehicles.

5 The main object of this invention is to provide a simple, durable and efficient collapsible device readily attachable to a running board and adapted to be raised to one set position to serve as a luggage carrier and 10 adapted, further, to be expanded to provide a convenient table. Further objects of our invention and its usefulness are hereinafter fully set forth, reference being had to the accompanying drawing in which,—

15 Fig. 1 is a top view of our collapsible rack and table device folded up and attached to a running board of an automobile or other flat horizontal element.

Fig. 2 is a right hand end elevation of our 20 device in Fig. 1 but fully extended to serve as a table.

Fig. 3 is a front view of the right hand end of the device fully extended and looking as toward Fig. 2 from the left, showing 25 certain details of construction more clearly.

Fig. 4 is a perspective view of our device in operative position as a table on the running board of a car, showing portions of adjacent parts of a car body.

30 Referring to the drawing by reference numerals, 5 designates a preferred article to which our device is attached namely one of the running boards at the side 6 of a motor vehicle, said board in most cases, particularly 35 on so-called pleasure cars, being about 12 to 16 inches above the ground and in horizontal plane.

The device comprises two U-shaped clamping members 7 adapted to straddle the running board 5 transversely and clamped there-to each by suitable set screws 8 engaging the under side of board 5. Said clamps are parallel and in spaced relation each provided with an aperture in the upper part of its 45 closed end for receiving a pivot bolt 9, said latter bolts engaging in apertures at the opposite lower part of end members of an elongated quadrangular open frame 10 preferably made of angle-iron. The clamp members are spaced slightly from the adjacent

end parts of the frame 10 and said space receives a folding two armed brace 11 pivotally secured with one end to the clamp as at 12 and its opposite end likewise secured as at 13 to the upper corner part of the adjacent 55 end of the main frame. In Fig. 1 the mid braces are shown folded with the main frame lying horizontally between the upper arms of the two clamps and in Figs. 2 and 4 the frame 10 is raised to vertical showing the 60 brace 11 extended. Thus is provided a simple collapsible luggage carrier, it being understood that as such the space within the upright frame 10 is closed by a foldable element which will now be described. 65

14 are two counterpart triangular braces each comprising a short vertical post pivotally mounted between the long parallel bars and near one end bar of the main frame 10, as at 15, and an integral upper arm 14A extending from said post at right angles. Each said brace comprises further an inclined brace 14B and smaller interior braces 14C, all in common plane and providing a light triangular frame of ample strength. It is 70 75 obvious that these pivoted triangular braces may be made in a number of other ways equally efficient to that shown.

Both braces may be swung to lie flat within main frame 10 and may overlap each other, as best shown in Fig. 1. In frame 10, above said pivoted braces we provide a multi-leaf sectional table top, all sections of which are hinged to each other and the top section further hinged as by means of hinges 80 85 16 to the upper long bar of the main frame 10. For illustrative purpose a three section table top is shown comprising a top section A, hinged at 16 as described, a middle section B connected to A as by a piano hinge 90 95 17 and an outer section C hingedly connected to the opposite edge of section B also preferably by a piano-type hinge 17'. The free edge of the outer section is preferably reinforced by a light angle-iron 18. The sections A, B and C are of such sizes that they may be folded up to lie flat against each other, by swinging them as indicated by arrows 19 in Fig. 2. Then the hinges 16 serve as a common hanger for all the sections 100

(folded) and which may thus be laid flat on top of the folded braces 14, within the frame 10, when the latter lies flat on the running board.

When it is desired to have the device serve as a table the main frame is first raised to vertical plane, as in Fig. 2, then the hinged-ly connected table top sections A, B and C are unfolded and extended outwardly, after which the braces 14 are swung out from frame 10 and at right angles thereto, to support the opposite end parts of the table top sections simultaneously.

20 represents any suitable type of flexible means such as a chain, one for each support frame 14 one end of which chain is secured to a lower bar of the main frame, near one end of said frame, and its other end attached to a lower part of brace 14B of the adjacent brace frame, to limit the outward swinging of the latter.

21 is a catch member at each outer corner of the table part C, comprising preferably an outwardly opening channel shaped piece fixed on the said part on its under side. The limit of outward movement of each brace frame should be such that the said brace must be sprung out from its normal outer position, as to dotted line position 14* in Fig. 3 which brings the extreme outer end of brace 14 outwardly of the catch member 21 which is subsequently engaged when member 14 is released and springs back, as to full line position in Fig. 3 and as also shown in Fig. 2. Thus the extended table top not only rests on said braces 14 but it engages frictionally at its outer corners, simultaneously and a rigid, and convenient table is provided at the side of an automobile.

In Figs. 1 and 3, 22 is a close coil spring with opposite hook members, one engaging each chain 20 and the other hook member thereof adapted to be engaged in an aperture 23 or equivalent means on the top section A of the table when the table leaves or sections are folded and laid within frame 10, the spring 22 being of course then in tension to hold said table top sections down securely in place. Other means may be used for holding the folded device down flat on the running board. It is now clear that our device is very compact when in folded position, lying flat on the running board in a plane not high enough to interfere with opening or closing of car doors. As designed, in substantial materials, the device can be stepped on when folded flat, without damage. As a luggage carrier the main frame is of course raised only to vertical position with the folded table top sections remaining therein and serving as an outer wall for the device when used as a luggage carrier.

We claim:

65 In combination, a portable luggage car-

rier and table comprising a pair of end brackets detachably securable transversely on a horizontal flat element, a quadrangular main frame pivotally mounted to and between said brackets and adapted to be swung from a flat plane between said brackets to a vertical plane, knee joints connecting each said bracket to an adjacent part of said frame and limiting movement of the latter to an upright position, a sectional, collapsible table top pivotally connected to the upper horizontal edge part of said main frame remote from its hinged connection with the brackets, table supporting brace pivotally mounted in said frame and adapted to be swung out therefrom to support the table top in extended condition and in a horizontal plane, said sectional table top comprising a series of flat plates hingedly connected to each other and all adapted to be selectively folded against each other or extended outwardly in horizontal plane, and a reinforcing element at the free edge of the outermost plate, and brace engaging means fixed to the outer corner parts of said latter plate to be engaged inwardly by the outermost parts of said braces, simultaneously, and said braces comprising in part an upper horizontal bar adapted to support the end edges of the table plates.

In testimony whereof we affix our signatures.

ERNEST STROM.
